[57] CLAIM

The ornamental design for a nurser sac holder, as shown and described.

DESCRIPTION

FIG. 1 is an exploded perspective view of a nurser sac holder, showing my new design;

FIG. 2 is a second perspective view of the assembled nurser sac holder of FIG. 1, from an angle different from that of FIG. 1;

FIG. 3 is a front view of the nurser sac holder of FIG. 1;

FIG. 4 is a rear view of the nurser sac holder of FIG. 1;

FIG. 5 is a first side view of the nurser sac holder of FIG. 1, wherein a second side view would be a mirror image thereof;

FIG. 6 is a top view of the nurser sac holder of FIG. 1;

FIG. 7 is a bottom view of the nurser sac holder of FIG. 1;

FIG. 8 is an exploded view of the nurser sac holder showing the bottle holder and plunger;

FIG. 9 is a perspective view of the cap of the nurser sac holder; and,

FIG. 10 is a perspective view of the retaining ring of the nurser sac holder.

The broken line showing of the nipple in FIGS. 1 and 10 is for illustrative purposes only and forms no part of the claimed design.
